MULTIPLE ROLL MILL WITH MEANS FOR
SPACING THE ROLLS WHILE BEING RO-
TATIVELY DRIVENMarley G. Hill, Brooklyn, N. Y., assignor to
Charles Ross & Son Company, Brooklyn, N. Y.,
a corporation of New York

Application October 28, 1949, Serial No. 124,221

6 Claims. (Cl. 241—233)

1

My invention relates broadly to roller mills for grinding and dispersing paint and the like, and more particularly to an improved construction of roller mill including means for precisely adjusting the relative positions of the rolls.

One of the objects of my invention is to provide an improved roller mill for grinding and dispersing paint in which a multiplicity of rolls are arranged to operate at differential surface speeds to impart rubbing or dispersing action to the paint, with yieldably adjustment means for controlling the spacial relation of the rolls.

Still another object of my invention is to provide an improved construction of roller mill for grinding and dispersing paint including at least three coating rolls driven at widely different speeds and adjustable one with respect to another through screw adjustment means and operative to feed paint to the nip of two of the differentially operating rolls for delivery over the surface of the third differentially operating roll.

Still another object of my invention is to provide a construction of regulated grinding and dispersing mill for paint and the like in which a rubbing and dispersing action is obtained over the surfaces of a multiplicity of coating rolls where the paint to be ground is delivered to the nip of two of the rolls and collected from the surface of a coating roll in a thoroughly ground and dispersed form, and the spacial relation of the rolls controlled with a high degree of precision to meet variable characteristics encountered in different paints.

Still another object of my invention is to provide a construction and arrangement of improved roller mill for grinding and dispersing paint and the like including a multiplicity of coating differentially driven rolls where the rolls are mounted for relative adjustment, the adjustment means for both ends of the rolls being operated from one end of the mill.

Still another object of my invention is to provide an improved construction of adjustment means for the individual rolls of a multiple-roll mill, in which the relative adjustment of the rolls is controllable by a manually controlled device from one end of the mill without going to opposite ends of the mill to make individual adjustments of the positions of the roller bearings.

Still another object of my invention is to provide a construction of roller mill employing a multiplicity of coating rolls in surface contact one with another, including means for selectively controlling the spacial relation of the rolls while the rolls are being rotatively driven.

2

Other and further objects of my invention reside in the construction of a compact grinding and dispersing mill unit as set forth more fully in the specification hereinafter following, by reference to the accompanying drawings, in which:

Figure 1 is a side elevational view of the grinding and dispersing roller mill of my invention; Fig. 2 is a top plan view of the roller mill; Fig. 3 is a side elevational view partially broken away and shown in section on line 3—3 of Fig. 2, showing more particularly the drive to the front roll; Fig. 4 is a detailed perspective view showing the eccentric arrangement for one set of rolls only; Fig. 5 is a horizontal sectional view showing particularly the arrangement of the front roll, the middle roll and the back roll; Fig. 6 is a detail sectional view of the back roll; Fig. 7 is a detail sectional view of the front roll; Fig. 8 is a fragmentary vertical transverse sectional view taken substantially on line 8—8 of Fig. 9 showing more particularly the means employed for accomplishing the eccentric adjustments; Fig. 9 is a horizontal sectional view taken substantially on line 9—9 of Fig. 8; Fig. 10 is a vertical sectional view taken longitudinally of the middle roll taken on line 10—10 of Fig. 2; Fig. 11 is a detail sectional view showing more particularly the mechanical construction of the middle roll, and the arrangement of temperature control means therein; Fig. 12 is an end elevational view of the roller mill on a somewhat smaller scale; Fig. 13 is a vertical transverse sectional view taken substantially centrally of the roller mill substantially on line 13—13 of Fig. 2, showing more particularly the coating rear, middle and front rolls, together with the coating scraping knife; Fig. 14 is a transverse vertical sectional view showing more particularly the arrangement for driving the rolls, in this particular illustration the motor shaft being shown in section and driving the front roll through a sprocket chain; Fig. 15 is a similar view to Fig. 14, but looking from the side and showing more particularly the driving means for the middle and rear rolls; Fig. 16 is a theoretical view showing the path of travel of the paint through the roller mill during a grinding and dispersing operation; Fig. 17 is a fragmentary perspective view illustrating the manner of supporting the right hand end of the rolls from the main frame as viewed in Fig. 10; Fig. 18 is a view illustrating the manner of supporting the right hand ends of the rolls from the main frame of the mill as viewed in Fig. 10; Fig. 19 is a top plan view of the supports for the rolls with the casting of the machine illustrated in transverse sec-

tion, the view being taken substantially on line 19—19 of Fig. 18; Fig. 20 is a horizontal sectional view taken substantially on line 20—20 of Fig. 18 with the roller bearing supports and the plate members omitted for clarification; and Fig. 21 is a perspective view of the bearing support in which the right hand ends of the transversely extending cam shafts are journaled.

Referring to the drawings in detail, reference character 1 designates the main frame of the roller mill, which forms at 1a the lower supports for the bearings for the middle roll 2. The top portions of the bearings for the middle roll 2 are illustrated more particularly in Fig. 8 by plate members 3. The plate members 3 in turn form supports for the bearings for the front roll 4 and the rear roll 5, by means of pins 6 and 7, which enter the front roll bearing support 8 and the rear roll bearing support 9, as represented in Fig. 8. These bearing supports are all located at opposite ends of the rolls and into which the reduced section ends of the rolls extend. The bearing supports 8 and 9 are pendently suspended from the plate members 3, and are free to move about the pins 6 and 7 as axes, for adjustment of the front and rear rolls with respect to the middle roll. The rear bearing support 8 and front bearing support 9 both include dependent lug portions 10 and 11 thereon displaced from the vertical axis of the roll bearings carried thereby, which are slotted at 10a and 11a for the passage of the roll adjustment screws 12 and 14. The roll adjustment screws 12 and 14 extend from the cam bearings 15 and 16 located adjacent opposite ends of the rolls, as shown more particularly in Figs. 4 and 8-10. The cam bearings 15 and 16 surround the transversely extending shafts 19 and 20 adjacent opposite ends thereof. The transversely extending shafts 19 and 20 have their ends 19a and 20a projecting eccentrically through journals at opposite ends of the shafts in bearing supports 21 and 22 adjacent the horizontally extending partition plate 1d of main frame 1 and immediately below the frame portion 12 which extends beneath the rolls 2, 4 and 5.

The bearing support 21 for the left hand ends of transversely extending shafts 19 and 20 is integral with the horizontally extending partition plate 1d of the main frame 1. The bearing support for the right hand ends of shaft 19 and 20 is shown more clearly in Fig. 21 and is in the nature of a bracket having horizontally extending bearing apertures 22a and 22b therein for supporting the ends 19a and 20a of the transversely extending shafts 19 and 20. The bearing support 22 is secured through the side of the main frame 1 and attached thereto by means of lugs 22c and fastening bolts and nuts. The bearing support 22 has a horizontally extending integral portion 22d which extends beneath the lower support 1a on the right hand end of the horizontally extending top portion of the main frame shown at 1e, and is connected therewith by the through-bolts 3b extending through plate member 3 and screw threaded into screw threaded apertures in the horizontally extending integral portion 22d of bearing support 22. Thus the right hand ends of shafts 19 and 20 receive ample bearing support both from the horizontally extending top portion of the main frame at 1e immediately beneath lower support 1a and also from the side wall of the main frame 1.

One end of the shafts 19 and 20 projects outside of the cover member 23 for the right hand

gear casing 24, and is provided with manually controllable lever members 25 and 26, adapted to be adjusted angularly over the quadrantal guides shown at 27 and 28 in Fig. 12. By movement of the manually controllable levers 25 and 26 the rolls are selectively oriented as shafts 19 and 20 move about their eccentric extensions 19a and 20a, which in turn impart movement to the cam bearings 15 and 16, respectively, thereby displacing the roll adjustment screws 12 and 14. The roll adjustment screws 12 and 14 extend through coil springs 29 and 30 and through the apertured plate members 31 and 32 and through the slots 11a and 10a in depending lug portions 11 and 10 of the front and rear bearing supports respectively, and form yieldable connections between cam bearings 15 and 16 and the lug portions 11 and 10 of the roll bearing supports 8 and 9. The roll adjustment screws 12 and 14 then pass through roll adjustment spacer members 33 and 34, which have substantially spherical end surfaces 33a and 34a which engage within socket-like recesses in the depending lug portions 11 and 10, as represented at 11b and 10b, which function as bearings when roll adjustment screws 12 and 14 are oscillated by the eccentric action of the cam bearings 15 and 16 respectively. Adjustable nuts 12a and 14a are secured over the ends of the roll adjustment screws 12 and 14 and bear against the roll adjustment spacer members 33 and 34. The ends of the roll adjustment screws 12 and 14 may be displaced into the offset end caps 1b and 1c carried by the main frame 1. Thus, a very precise movement is imparted to the front and rear rolls 4 and 5 by movement of the manually controllable levers 25 and 26. The front and rear rolls 4 and 5 may thus be linearly advanced or retracted from the middle roll 2. The cover member 23 for the right hand gear casing 24 and the cover member 35 includes all of the adjusting parts of the mechanism which I have described. A left hand casing 36 is removably mounted at the left hand end of the main frame and serves to streamline the appearance of the roller mill, at the same time providing ready access to the electric motor 37 mounted within the main frame 1. The right hand gear casing 24 and the left hand casing 36 are provided with louvres 24a and 36a, respectively, for the circulation of cooling air through the roller mill. Removable liner or oil pan 38 is mounted within the casing 24 as shown in Fig. 10.

The motor 37 is mounted on plate 40 secured to main frame 1 through support 41. The motor shaft 42 carries pinion 43 thereon, which engages the sprocket chain 44, driving gear 45 carried by front roll 4 tensioned by idler wheel 46 carried by shaft 47. The front roll 4 carries on the end thereof opposite to the end represented in Fig. 14, the pinion 48. Pinion 48 at the end of the roller mill opposite the end of the roller mill at which gear 45 is located, meshes with gear 49 carried by the middle roll 2, as shown in Figs. 15 and 5. The middle roll 2 carries on the end thereof remote from the end carrying gear 49 the pinion 50, as shown in Figs. 14 and 5. The pinion 50 meshes with gear 51 carried by the rear roll 5, as shown in Figs. 15 and 5; thus the rolls are simultaneously driven from motor 37 and in a particular ratio which I have found productive of particularly efficient operation. The front roll 4, rear roll 5 and middle roll 2, by virtue of the gearing which I have described, have imparted thereto differential speeds in a ratio of

approximately 3 to 1. That is, the rear roll 5 revolves at approximately 30 R. P. M., the middle roll 2 rotates at approximately 90 R. P. M., and the front roll 4 revolves at approximately 270 R. P. M. This ratio of speeds, obtainable by the arrangement of gearing which I have described, is important, because of the necessity for the dispersing action in paint to which I have heretofore alluded.

The process of operation is illustrated in Fig. 16 where the material represented at 52 is deposited in the valley between the rear roll 5 and the middle roll 2, and is confined therein by end plate regulators or color blades 53 and 54, shown particularly in Figs. 1 and 10 and 13. Color blades 53 and 54 are adjustable toward and away from rear and middle rolls 5 and 2, and also adjusted linearly of the rear and middle rolls 5 and 2, by mounting means represented more clearly in Figs. 1, 2, 10 and 13. A frame 55 is supported on standards 56 and 57 which are erected on cover members 23 and 35, and have a linearly extending bar member 58 therebetween. The bar member 58 is provided with spaced linear slots 59 and 60 therein, through which screw members 61 and 62 extend. Screw members 61 and 62 are fastened to the color blades 53 and 54 and are provided with wing nuts 61a and 62a thereon by which the color blades may be secured in predetermined position according to the character of the mix which is supplied to the rolls. The mix may thus be confined to a certain area of the rolls, either centrally therein, or at one side thereof in a trough. Due to the rotation of the rear roll 5 and the center roll 2 toward each other and downwardly, that is, rear roll 5 revolving in a clockwise direction while middle roll 2 revolves in a counterclockwise direction, the material 52 indicated in Fig. 16 is drawn between the nip of the rolls at the junction 63 thereof. Due to the differential speeds of the rolls at their surfaces, the material is given a rubbing or dispersing action somewhat similar to the mortar and pestle action utilized by apothecaries. The middle roll 2 having a greater speed than the rear roll 5 causes the larger portion of the material 52 to adhere to the surface of middle roll 2 in a thin film, which is drawn around the middle roll 2 and up to the center where it is dispersed again by contact at 64 with the front roll 4. The front roll 4, in turn being driven at a still greater speed, tends to remove the film of material from the surface of the middle roll 2 and it is transmitted on the upper surface of the front roll 4 until it comes in contact with the apron represented at 65, which is provided with a scraper knife 66 which scrapes the material off the surface of front roll 4 in thickness less than .001", as best shown in Figs. 13 and 16. From this process it is apparent that the capacity or production of the mill is governed by the speed which in turn is governed by the adhesive qualities of the material to adhere to the fast or front roll 4 as this factor determines the amount of material which will leave the roll by centrifugal force. The fact that the roll surfaces are always traveling in the same direction as they contact each other and at differential speeds, produces the dispersing action.

Apron 65 is mounted with respect to the main frame 1 of the roller mill as shown more clearly in Fig. 13, wherein apron 65 is in the form of an outlet chute tapered to the discharge end 65a thereof, shown in Figs. 1 and 2, and supported by screw adjustment stud 67 having an adjustment nut 68 thereon and passing through a coil

spring 69 and through sleeve 70 and into the socket 71 in the main frame 1. The screw adjustment stud 67 has a head 72 thereon supporting the underside of the apron 65 near the discharge end 65a therein. The upper end of the apron 65 is provided with lugs 65b, which are slotted as represented at 65c, and through which securing screws 73 pass. Apron 65 is fulcrumed around screw 73, so that adjustment of nut 68 on screw adjustment stud 67 serves to control the position of the scraper knife 66 with respect to the rotating surface of front roll 4 for shearing the layer of paint from the high speed surface of front roll 4 for discharge through the discharge end 65a. The slot 65c facilitates assembly of the chute 65 in a position for effecting the shearing of the film from the surface of front roll 4.

The rolls 2, 4 and 5 are controllable with respect to temperature, for obtaining a condition of operation most efficient for the grinding and dispersing of the material. This is accomplished by constructing the rolls in tubular form, with one end of each of the rolls plugged or obstructed, as represented by plugs 5a, 2a and 4a in Fig. 5. Into the hollow interior of each of these rolls I extend an injection tube represented at 74, 75 and 76. The injection tubes connect through individual valves 77, 78 and 79 with a manifold 80, which extends transversely of the rolls within the drain housing 81 to a position beyond the drain housing where the manifold is provided with a master valve 82 and a connection leading to the supply line 83. The drain housing 81 is apertured at the end thereof in alignment with the individual valves 77, 78 and 79, which are controllable through hand wheels 77a, 78a and 79a, to allow entry of the temperature controlling medium to the individual rolls. The drain housing 81 is provided with a cover portion 81a which may be raised to the dotted line position 81a' shown in Fig. 10 in securing access to the interior of the drain housing 81. The drain housing 81 is connected through a waste pipe 84 with the waste for discharging the temperature controlling medium. For purposes of maintaining the required operating temperature of the rolls, I may use water for cooling the rolls, or compressed air, or steam may be introduced through the injector tubes. The important point is that the rolls are individually controllable as to temperature through individual valves interposed between the supply manifold and the injector tubes. In each instance the open ends of the rolls 2, 4 and 5 receive the injector tubes. In order to guard against leakage of the temperature controlling medium, at the extreme end of the rolls I provide tubular sleeve members shown at 2b, 4b and 5b, fitting within the internal bore of the respective rolls 2, 4 and 5 and extending beyond the cover member 35 and into the drain housing 81, terminating in outwardly extending flanges 2c, 4c and 5c respectively. The internal bores of the tubular sleeves 2b, 4b and 5b are such that displacement of the rolls 2, 4 and 5 may be effected with respect to each other, because adequate clearance is provided between the injector tubes and the interior walls of the tubular sleeves.

One of the advantages arising out of the construction embodied in the roller mill of my invention is the fact that adjustment of the special relation of the rolls may be effected while the roller mill is in operation, and without shutting down the roller mill, which may be necessary in structures requiring individual adjustment of

the bearings at each end of the roller mill. The limits of adjustment are always within the limits of the inter-engagement of the driving gear teeth, so that these adjustments are of film thickness limits. Moreover, the rolls may be selectively adjusted with respect to each other by reason of the individual control provided by manually controllable levers 25 and 26, permitting separate degrees of adjustment between front roll 4 and middle roll 2, or between rear roll 5 and middle roll 2, enabling the results of the grinding and dispersing operation to be readily observed by the operator while adjustments are being made from the same point, and while the roller mill is running. To facilitate such precise adjustment the manually controllable levers 25 and 26 are provided with detents such as represented at 25a and 26a in Figs. 1 and 2, which bear frictionally against quadrant guides 27 and 28 for selectively maintaining the manually controllable levers 25 and 26 in the positions in which they are set.

Throughout the drawings I have indicated bearings for the opposite ends of the rolls. I desire that it be understood that these may be roller bearings or ball race bearings. Fig. 10 shows how the rolls are assembled in the bearings in a way in which the rolls may be removed and replaced for servicing. The left end of the middle roll 2, as viewed in Fig. 10, is supported in a bearing 3a in left plate member 3. The left plate member 3 is supported from the main frame 1 by a lower support 1a integral with the main frame 1 similar to the right hand end of the machine shown in detail in Fig. 8. Suitable securing bolts may extend through lower supports 1a into the plate members 3 to maintain the relative position of the middle roll with respect to the front roll 4 and rear roll 5. The front and rear rolls 4 and 5 may now have their left hand ends inserted through the bearing in bearing supports 8 and 9 that are suspended from the left hand plate member 3.

The right hand plate member 3 is inserted over the right hand roll 2 so that end bearing 3a in right hand plate member 3 encircles the right hand end of middle roll 2. The right hand plate member 3 is then aligned with and supported on lower support 1a which is mounted on bearing support 22 secured to main frame 1 as shown at the right of Fig. 10. Suitable fastening bolts may extend through lower support 1a into the right hand plate member 3. The bearings for the right hand ends of front and rear rolls 4 and 5 are slipped over the right hand ends of these rolls during the assembly of the right hand plate member 3 over the end of the middle roll. The assembly is now ready for adjustment which is accomplished as heretofore explained by manipulation of the adjustment screws 12 and 14 for adjusting the relationship of the rolls. The cover members 23 and 35 are now positioned on the machine preparatory to operation of the machine.

The lower supports 1a at opposite ends of the rolls are integral with the main frame 1 at each end of the rolls as shown more particularly in Figs. 17-20. The lower supports 1a are integral with the horizontally extending top portion of the main frame 1 shown at 1e and carry the weight of the rolls from the main frame of the machine. The plate members 3 are supported by the lower supports 1a that are integral with the main frame 1 of the mill. The plate members 3 are secured in position on lower supports 1a by means of fastening bolts 3b that extend through

the plate members 3 and enter screw threaded openings in supports 1a. Thus solid support is provided for the plate members 3 directly from the solid wall of the main frame 1 and the extension thereof through the horizontally extending top portion 1e and the upwardly curved flat supports 1a integrally connected therewith. The supports 1a are sufficiently narrow in width to enable these supports to extend beneath the front and rear rolls 4 and 5 and between the axes thereof. In each instance the bearings are supplemented by oil seals which I have indicated at 85 and 86. There is a pair of oil seals for each end of the rolls and oil seals 86 immediately adjacent the ends of the roll are provided to prevent foreign material from entering along the roll journal. Oil seals 85 prevent oil from leaving the housing. I have schematically shown both oil seals carried by the same ring housing but it will be understood that individual ring housings carrying the individual oil seals may be provided and in fact in many instances are preferred.

I have found the roller mill of my invention highly practical in the production of thoroughly mixed and dispersed pigments and paints. The case by which the rolls are spacially controlled from one end of the mill, making it unnecessary to go to opposite ends of the mill to individually adjust the bearings of each of the rolls, renders the roller mill very practical in use. Also, the roller mill or machine is very compact, and in the structure illustrated it is entirely practical to construct the machine within an over-all length of 33"; an over-all width of 24"; an over-all height of 30"; and utilize a motor of one hp. The weight of such a machine is approximately 800 lbs. I have constructed larger size machines generally distinguished by roll diameter and face such as 4 1/2" x 10", 8" x 18" and 14" x 32". These sizes are given by way of examples and without intending to restrict my invention in any way to this range of sizes.

While I have described my invention in certain of its preferred embodiments, I realize that modifications and changes will readily suggest themselves to those skilled in the art, and I desire that it be understood that no limitations upon my invention are intended other than may be imposed by the scope of the appended claims.

What I claim as new and desire to secure by Letters Patent of the United States, is as follows:

1. A roller mill for grinding and dispersing paint and the like comprising a frame structure, a middle roll, journals for said middle roll carried by said frame structure, suspension plates extending from the journals of said middle roll, means supporting said suspension plates from said frame, roll bearing supports pivotally and pendentially suspended by said suspension plates, front and rear rolls journaled in said roll bearing supports on opposite sides of said middle roll, lug portions depending from said roll bearing supports and resilient means engaging said lug portions for controlling the positions of said roll bearing supports with respect to said middle roll for yieldably controlling the spacial relation of said front and rear rolls with respect to said middle roll, and cam bearings yieldably connected with the lug portions of said roll bearing supports and disposed in a plane extending beneath said rolls.

2. A roller mill for grinding and dispersing paints and the like comprising a frame structure, a middle roll, journals for said middle roll carried by said frame structure, suspension plates

extending from the journals of said middle roll, means supporting said suspension plates from said frame, roll bearing supports pivotally and pendently suspended by said suspension plates, front and rear rolls journaled in said roll bearing supports on opposite sides of said middle roll, lug portions depending from said roll bearing supports and resilient means engaging said lug portions for controlling the positions of said roll bearing supports with respect to said middle roll for yieldably controlling the spacial relation of said front and rear rolls with respect to said middle roll, wherein said means engaging the said lug portions on said roll bearing supports include yieldably connected cam bearings, shaft members extending substantially parallel to said rolls and beneath said rolls, eccentric cams carried by said shaft members and engageable with said cam bearings and manually controllable levers on said shaft members for revolving said shaft members and imparting movement to said eccentric cams for correspondingly moving said cam bearings and adjusting the position of said roll bearing supports and the spacial relation of said rolls.

3. A roller mill for grinding and dispersing paint and the like comprising a frame structure, a middle roll, journals for said middle roll carried by said frame structure, suspension plates extending from the journals of said middle roll, means supporting said suspension plates from said frame, roll bearing supports pivotally and pendently suspended by said suspension plates, front and rear rolls journaled in said roll bearing supports on opposite sides of said middle roll, lug portions depending from said roll bearing supports and resilient means engaging said lug portions for controlling the positions of said roll bearing supports with respect to said middle roll for yieldably controlling the spacial relation of said front and rear rolls with respect to said middle roll, wherein said lug portions are bifurcated at the terminating ends thereof and in which the means engaging said lug portions extend through said bifurcated ends and operate to pendently swing said roll bearing supports about the pivotal suspensions thereof in said suspension plates.

4. A roller mill for grinding and dispersing paint and the like comprising a frame structure, a middle roll, journals for said middle roll carried by said frame structure, suspension plates extending from the journals of said middle roll, means supporting said suspension plates from said frame, roll bearing supports pivotally and pendently suspended by said suspension plates, front and rear rolls journaled in said roll bearing supports on opposite sides of said middle roll, lug portions depending from said roll bearing supports and resilient means engaging said lug portions for controlling the positions of said roll bearing supports with respect to said middle roll for yieldably controlling the spacial relation of said front and rear rolls with respect to said middle roll, wherein said lug portions are bifurcated at the terminating ends thereof and are provided with socket-like recesses in the faces thereof remote from the axes of said front and rear rolls

and in which the means engaging said lug portions are constituted by roll adjustment members extending through the bifurcated ends of said lug portions, spacer members surrounding said roll adjustment members and adjustably fitting into the socket-like recesses in the faces of the bifurcated ends of said lug portions, said roll adjustment members extending through said spacer members, and means for adjustably assembling 10 said roll adjustment members with respect to said spacer members for allowing limited displacement between said roll adjustment members and said lug portions.

5. In a roller mill, a frame structure including 15 parallel extending spaced side plates, a middle roll journaled centrally between said side plates on an axis normal thereto, pairs of roll bearing supports pivotally connected with said side plates in positions substantially above the axis of said 20 middle roll and laterally spaced on opposite sides of said middle roll, roll bearings carried by said roll bearing supports, with the roll bearing in the roll bearing support on one of said side plates transversely aligned with the roll bearing in the 25 roll bearing support on the opposite side plate, transverse rolls journaled in the transversely aligned roll bearing supports and coacting with said middle roll, depending bifurcated extensions on the lower ends of said roll bearing supports 30 below said last mentioned rolls, and yieldable means engaging said depending bifurcated extensions for adjusting said roll bearing supports toward or away from the axis of said middle roll for varying the spacial relation of the transverse 35 rolls carried by said aligned roll bearing supports with respect to said middle roll.

6. A roller mill as set forth in claim 5 wherein 40 the depending extensions on said roll bearing supports are displaced from the vertical axes of the roll bearings carried by the roll bearing supports in a direction away from a center line passing through the pivotal connections of said roll bearing supports with said side plates, providing a turning moment for substantially horizontal 45 forces exerted on the lower ends of the extensions about said pivotal connections for swinging the transverse rolls toward or away from said middle roll, and wherein the means which engage said depending extensions are yieldable for allowing limited displacement between the rolls after 50 selected setting of the spacial relation thereof.

MARLEY G. HILL.
